and Alexander Mason
Attest.

United States Patent Office.

JOHN CHAPPLE, OF JASPER, NEW YORK.

Letters Patent No. 98,924, dated January 18, 1870.

IMPROVEMENT IN CHURNS.

The Schedule referred to in these Letters Patent and making part of the same.

To all whom it may concern:

Be it known that I, JOHN CHAPPLE, of Jasper, in the county of Steuben, and in the State of New York, have invented certain new and useful Improvements in Churns; and do hereby declare that the following is a full, clear, and exact description thereof, reference being had to the accompanying drawing, and to the letters of reference marked thereon, making a part of this specification.

The nature of my invention consists in the construction and arrangement of a churn, of the kind known as the revolving-barrel or firkin-churn; and also in the construction of the bed or platform for said churn.

In order to enable others skilled in the art to which my invention appertains, to make and use the same, I will now proceed to describe its construction and operation, referring to the annexed drawings, in which—

Figure 1 is a perspective view of the churn, in proper position upon the bed or platform for burning;

Figure 2 is a horizontal section of the churn; and

Figure 3 is a section of the churn, showing the manner of fastening the lid or cover.

A represents the churn, which consists of a series of staves, of sufficient length and width to make the churn of the desired height and diameter, with a head or bottom, B, firmly secured at one end.

The churn is held together by bands or hoops C C.

I then make a solid lid or cover, D, surrounded with a wide band or hoop, a, projecting below the lid or cover a sufficient distance, and this band or hoop is small enough to fit inside of the upper main hoop C to the churn.

Under the upper edge of this upper band or hoop, is cut a channel or space large enough for a rubber ring, b, or a ring of any other suitable flexible material, so as to make a water-tight joint, as the band or hoop a of the lid D is pressed down on to it by means of the hinged straps E, that pass over the top of the lid or cover and down on to the wedge-loops d, which are secured to the side of the churn A.

On the lid D is attached a crank and bearing, G, with a ring or collar, e, on it, to prevent end-play to the churn as it revolves; and on the opposite end or bottom C of the churn, is a flanged gudgeon, f, which forms the bearing for that end of the churn as it revolves.

H represents a bed or platform, having at one end

a suitable standard, I, upon which the crank and bearing G is placed.

At a suitable point on the bed H is hinged a standard, J, upon which, when raised, the flanged gudgeon f rests.

The standard J is channelled out, as shown in fig. 1, for the flange of the gudgeon, so that the standard may be let down on to the flat bed H, and the flange not be in the way. This flange on the gudgeon is also of great importance in turning back the standard to its proper position when the churn is to be revolved upon its axles, and prevent the gudgeon from drawing off from the standard. This standard or hanger is so constructed as to answer a double purpose, and can be quickly changed from a hanger to a platform, for the churn to rest or stand on, by only taking the crank-end of the churn out of its bearing and setting it up on the gudgeon-end.

The inside of the churn A is made of a smooth material, and a sufficient number of beaters K K placed lengthwise of the churn, running to within a short distance of the bottom, and also of the lid of the churn, thereby giving the cream a chance to circulate around the ends of the churn, changing the cream into butter much quicker than other churning, and also gathering the butter more perfectly.

The stave and beater K, that projects into the churn, is all in one piece, the timber being thick enough for the stave and beater, making a solid arrangement.

Having thus fully described my invention,

What I claim as new, and desire to secure by Letters Patent, is—

1. The combination of the platform or bed H, stationary standard I, and hinged hanger or standard J, all substantially as and for the purposes herein set forth.

2. The combination of the churn A, hoop C, lid D, hoop a, ring b, strap E, and loop d, all constructed and arranged substantially as and for the purposes herein set forth.

In testimony that I claim the foregoing, I have hereunto set my hand, this 27th day of October, 1869.

JOHN CHAPPLE.
